DISPENSING TOP FOR A CONTAINER

Neil S. Waterman, Stamford, Conn., assignor to Atlantic Plastics, Inc., Stamford, Conn.

Filed Aug. 27, 1964, Ser. No. 81,470

Term of patent 14 years

(Cl. D58—26)

FIG. 1 is a perspective view of a dispensing top for a container showing my new design with the cover flaps in closed condition;

FIG. 2 is a perspective view with the cover flaps open;

FIG. 3 is a rear elevational view with the cover flaps in closed condition;

FIG. 4 is a side elevational view looking from the right of FIG. 3; and

FIG. 5 is a bottom plan view thereof.

I claim:

The ornamental design for a dispensing top for a container, substantially as shown.
